CLAIM

The ornamental design for an electronic device with graphical user interface for real time blood glucose changes as shown and described.

DESCRIPTION

1. Electronic device with graphical user interface for real time blood glucose changes

1.1 is a front view of a first embodiment of an electronic device with graphical user interface for real time blood glucose changes showing our new design;

2.1 is a front view of a second embodiment of the electronic device with graphical user interface for real time blood glucose changes; and

(Continued)

3.1. is a front view of a third embodiment of the electronic device with graphical user interface for real time blood glucose changes.
